TOOTH FOR EXCAVATING APPARATUS

Laurence Massa, Los Angeles, Calif.

Application January 27, 1942, Serial No. 428,405

4 Claims. (Cl. 37—142)

This invention relates to excavating machinery or other devices for handling material.

Machines used for excavating generally have a bucket or scoop which has a sharpened lip for scooping up the material being excavated. Some machines, such as ditchers and trenchers, are intended to produce an excavation of definite size, the width of the excavation being governed by the size of the series of scoops or buckets used to remove the material. Machines of this type are provided with teeth set around the cutting lips of the buckets. As the machine continues in service these teeth wear and become inefficient as digging instruments. Furthermore, as the teeth wear down unduly the body of the bucket drags over the walls of the excavation. In addition to causing inefficient digging and wear upon the bucket, the shortening of the teeth because of wear also results in the digging of an undergauge trench. Even a few inches of undergauge may require that the trench be widened by other means after the trencher has operated upon it.

In the past it has been the custom to provide removable, replaceable teeth on the edge of the buckets of excavating equipment, these teeth usually being held in place by bolts or other fastening means. It has also been suggested that removable tips be secured by holders which are in turn secured to the bucket, the tips being reversible after a certain amount of wear. However, all of the previous structures suffer from the disadvantage that when the teeth are worn to such an extent as to warrant their tips being reversed in their holders, such reversal places the new cutting edge of the teeth in such a position as to decrease the efficiency of the excavator as a whole, or else it causes the cutting of an undergauge trench in the case of machines for digging trenches or ditches.

In addition to the above disadvantages, machines which have removable and replaceable teeth, or reversible tips, either require a great deal of work in replacing these teeth or tips, or else the teeth are not efficiently held in place. For instance, the teeth may be held on the buckets by means of bolts, which require that two or more bolts be removed and replaced for every tooth changed, a time consuming operation in the case of a ditcher having a large number of buckets; or else the teeth are held in sockets of a tapered configuration, which have proved unsatisfactory because of the tendency of the teeth to be displaced during digging. That is, the teeth work out of their sockets un-

der the influence of the vibration and alternate stresses set up in the teeth as digging takes place.

With the above disadvantages of present day structures in mind, it is an object of the present invention to provide an improved tooth for excavating equipment which has a removable, reversible tip.

It is a further object of the present invention to provide a tooth having a removable tip which will stay in place without the use of auxiliary fastening devices.

It is a further object of the present invention to provide a reversible tooth tip which will cut after reversal along substantially the same line as the new tooth tip cut before reversal.

It is a further object of the present invention to provide a reversible tooth tip which will not entail substantial loss of gauge of a trench dug by a trencher upon reversal of the tip.

It is a further object of the present invention to provide a tooth tip and holder which depend upon the engagement of a tapered shank in a tapered socket to hold the tip in place, which will not loosen under digging stress.

This invention possesses many other advantages and has other objects which may be made more easily apparent from a consideration of one embodiment of the invention. For this purpose there are shown two forms in the drawing accompanying and forming part of the present specification. These forms will now be described in detail, illustrating the general principles of the invention; but it is to be understood that this detailed description is not to be taken in a limiting sense, since the scope of the invention is best defined by the appended claims.

Referring now to the drawing:

Figure 1 is a longitudinal section taken through a part of a bucket and a tooth mounted thereon;

Figure 2 is a view similar to that of Figure 1 showing the tip after it has been worn and reversed in its holder;

Figure 3 is a section taken on line 3—3 of Figure 1;

Figure 4 is a perspective view of the tip shown in Figures 1 and 3; and,

Figure 5 is a section similar to Figure 1 but of a modified form of construction.

As the present invention is adaptable to a wide range of different types of excavating equipment, and as it embodies principles which render it useful in all of these different types of equipment, a typical instance has been selected for illustration, but it is to be clearly understood

that the selection of this particular construction is not intended to be limitative but illustrative only. For this purpose the tooth has been shown as constituting one of the side teeth of a trencher. Figure 1 shows, in addition to a portion of the bucket and the tooth, a line 10-10 which represents the wall of the trench produced. It can be seen that as the tip of the tooth wears down the wall 10 is produced to the right of the position shown in Figure 1. Obviously, this would result in an undergauge trench. Furthermore, in machines not intended to dig to gauge, moving of this line 10 to the right would result in the body of the bucket or the tip holder dragging on the unexcavated earth which eventually wears the bucket unduly, and furthermore renders digging difficult and ultimately impossible. It is with the provision of means for preventing this change of the effective cutting line of the tooth with which this invention deals. As the cutting progresses, the tooth has a motion through the material being cut which has, in Figure 1, a downward component. This downward component of motion wears the cutting edge of the tooth until the tooth is worn to the dotted line 11 (Figure 1). When the tooth is worn to such an extent the back surface 11 of the tooth sliding along the excavated wall interferes with the digging action. It is customary to replace the tooth or otherwise provide a new cutting edge when the tooth reaches this condition. In the present instance this is done by simply reversing the tooth tip as shown in Figure 2. The edge 12 of the tooth tip then takes the position shown in Figure 2 and the back face 11 which formerly dragged along the excavated wall 10 then becomes the front cutting face of the tooth. It will be noted that the wall 10' in Figure 2 is the same distance from the body of the bucket as wall 10 in Figure 1. The relationship of the parts which permits this result is one of the important features of this invention. As shown in Figures 1 and 2, a tip holder 13 is secured to the body of the bucket and is provided with a tapered socket 14 for receiving the tip 16. This socket is at an angle to the excavated wall 10. For purposes of explanation, a center line 15 has been shown in Figure 1, this center line 15 being not the center line of the tooth as a whole but merely the center line of the socket 14. The tip 16 is provided with a tapered shank 17 for entry into the socket. If the center line 15 and the edge 12 have a certain relationship with the wall 10 the edge 12 will be placed against the wall 10 as the tooth tip is reversed. This relationship is best demonstrated by drawing a perpendicular to the center line 15 through edge 12. This perpendicular will intersect line 10 at point a and the center line at point b. If the distance a-b is equal to the distance between b and 12, reversal of the tip will place the edge 12 at point a. Thus, upon reversal of the tip, the tooth will dig along line 10, which is the desired effect of such reversal. It is to be understood that just before reversal the tooth will be digging along a line which is parallel to the line 10 but to the right thereof, and passing through the edge 12. The reversal thus increases the gauge of the trench by a distance which is equal to the distance between the line 10 and the edge 12. Reversal of the tooth on the opposite side of the bucket has a like effect. In the shown form this increase in gauge may not be very great,

being in the order of a few inches only. However, when heavy equipment is used the tooth tip 16 will be considerably thicker than that shown and thus this increase in gauge may be considerable.

5 In the shown device one method of achieving this relationship between the center line 15 and the edge 12 has been shown. The tapered shank 17 of the tooth tip is formed by having one face 11a bevelled with respect to the rest of the tip while the opposite face of the shank is a continuation of the face of the tip. That is, the face 18 of the tip continues to the rear end of the shank while the face 19 is bevelled from the point 10 20 rearwardly to form a taper with the face 18. It can be appreciated that this single bevelled surface to form a taper is merely an equivalent of bending the tooth at point 20. If desired the tapered shank may be set at other angles to the faces of the tip, depending on the thickness of the tooth, the amount of wear which will be tolerated before the tooth tip must be reversed, and other factors.

20 In securing tooth tips to holders by the use of 25 tapered shanks and sockets, it has been found in the past that the tips have a tendency to work loose. Accordingly in devices utilizing tapered shanks and sockets auxiliary fastening devices have customarily been employed to secure 30 the tips in place. I have found that the tendency of tapered shanks to work out of tapered sockets can be successfully overcome by the employment of tapered surfaces which are more or less parallel to the direction of maximum stress tending 35 to dislodge the tooth tip from its socket. In the present instance this maximum stress tending to dislodge the tooth tip naturally comes in a direction best indicated by the arrows in Figure 1. This stress tends to bend the tooth tip, and, if 40 ordinary tapered surfaces are used, will eventually cause the tip to work out of the socket. It is to be understood that the tendency to bend the tip does not, perhaps, actually bend it, but the alternating forces set up nevertheless tend to loosen the tip shank from the socket. For this reason the engagement of the surfaces 22 and 23 of the socket and the surfaces 18 and 11a of the shank are not particularly efficacious in holding 45 the tip in place. Accordingly, in the drawings, the shank is shown as having its side edges 50 formed with a taper. This taper is chiefly responsible for holding the tooth tip in place. I have also found that there is a definite range of tapers which may be utilized most satisfactorily 55 in this connection. The most efficient taper appears to be in the order of 0.6 inch per foot, or a taper of 0.05. However, the range appears to be between 0.015 and 0.15. Within this range the frictional forces are so related that the tooth has 60 no tendency to be displaced. This same taper may be applied to the front and back faces of the shank of the tooth tip.

65 The shown form of device with a bolted holder can be manufactured by modifying an existing tooth, the existing tooth being simply cut off and provided with a socket. If desired, the tooth may be made by providing a special socket welded directly to the bucket. This type of construction is shown in Figure 5. A socket portion 30 is secured to the bucket 31 by welding or the like. In order to prevent the weld from interfering with the shank of the tip when the tip is inserted in the socket a flange 32 is made integral with the socket 30. This flange 32 pro-

vides a suitable attachment point for the welding which secures the socket to the bucket. If the weld 33 is applied only around the edges of the flange 32 it does not interfere with the socket opening 30a.

What I claim as my invention is:

1. In a material handling device including a member movable through the material to be handled; a tooth comprising a support mounted on said member, an edged tooth tip, said tip and said support including means removably mounting said tip on said support for reversal by rotation about an axis at an angle to the path of movement of the edge of said tip, the perpendicular distance from said axis to a predetermined point on the front face of said tip being equal to the distance along the same perpendicular to the path of movement of the edge of said tip, whereby upon reversal of the tip after it has worn to produce a cutting edge at said predetermined point said cutting edge will be positioned in the path of movement of the original cutting edge.

2. In a material handling device including a member movable through the material to be handled; a tooth comprising a support mounted on said member, an edged tooth tip, said tip and said support having cooperating shank and socket for securing said tip to said support, the axis of said socket being at an angle to the path of movement of the edge of said tip, the perpendicular distance from said axis to a predetermined point on the front face of said tip being equal to the distance along the same perpendicular from the axis to the path of movement of the edge of said tip, whereby upon reversal of the tip after it has worn to produce a cutting edge at said predetermined point, said cutting

edge will be positioned in the path of movement of the original cutting edge.

3. In a material handling device including a member movable through the material to be handled; a tooth comprising a support mounted on said member having a socket, a tooth tip having a cutting edge and a shank for cooperative engagement with the socket in said support, the axis of said socket being at an angle 10 to the path of movement of the edge of the tip, the perpendicular distance from the axis of the socket to a predetermined point on the front face of said tip being equal to the distance along the same perpendicular to the path of movement of the edge of the tip, whereby upon reversal of the tip after it has worn to produce a cutting edge at said predetermined point said cutting edge will be positioned in the path of movement of the original cutting edge.
4. In a material handling device including a member movable through the material to be handled; a tooth comprising a support mounted on said member having a tapered socket, a tooth tip having a cutting edge and a tapered shank, 25 the taper on said shank being formed by a bevel on the rear face of said tip, the axis of said socket being at an angle to the path of movement of the edge of the tip, the perpendicular distance from the axis of the socket to a predetermined point on the front face of said tip being equal to the distance along the same perpendicular to the path of movement of the edge of the tip, whereby upon reversal of the tip after 30 it has worn to produce a cutting edge at said point, said cutting edge will be positioned in the path of movement of the original cutting edge.

LAURENCE MASSA.
